UNITED STATES PATENT OFFICE.

LARK ATHEN SPROUL, OF EDMOND, KANSAS.

ENSILAGE-HARVESTER.

1,308,818.

Specification of Letters Patent.

Patented July 8, 1919.

Application filed September 23, 1918. Serial No. 255,302.

To all whom it may concern:

Be it known that I, LARK ATHEN SPROUL, a citizen of the United States, residing at Edmond, in the county of Norton and State 5 of Kansas, have invented a new and useful Ensilage-Harvester, of which the following is a specification.

This invention relates to machines for harvesting and reducing it to ensilage, one of 10 the objects of the invention being to provide a machine for simultaneously cutting the standing corn in a desired number of rows, feeding the corn from the different rows to a single ensilage cutter, and directing the ensilage to a wagon or the like provided therefor, the entire operation taking place automatically without requiring handling by the operator.

Another object is to provide a machine of 20 this character which is compact in construction and can be controlled readily.

With the foregoing and other objects in view which will appear as the description proceeds the invention consists of certain 25 novel details of construction and combinations of parts which will be hereinafter more fully described and pointed out in the claims, it being understood that various changes may be made in the construction 30 and arrangement of the parts without departing from the spirit of the invention as claimed.

In the accompanying drawings the preferred form of the invention has been shown.

35 In said drawings—

Figure 1 is a plan view of the machine. Fig. 2 is a side elevation thereof.

Fig. 3 is a perspective view showing, diagrammatically, the power transmitting 40 mechanism of the machine.

Fig. 4 is an enlarged section on the line 4—4, Fig. 1.

Fig. 5 is an elevation of one side of the ensilage cutting mechanism.

45 Fig. 6 is an elevation of the other side thereof.

Fig. 7 is a plan view of a portion of one of the transverse conveyers and showing the harvesting mechanism combined therewith.

50 Fig. 8 is a section on line 8—8 Fig. 7.

Fig. 9 is a plan view of a portion of the longitudinal conveyer and showing its harvesting mechanism.

55 Fig. 10 is a transverse section through the longitudinal conveyer and a portion of the transverse conveyer.

Fig. 11 is an elevation of the inner side of one of the stalk gatherers with the chains removed.

Fig. 12 is a horizontal section there- 60 through.

Referring to the figures by characters of reference, 1 designates the frame of the machine having supporting wheels 2 and 3 to which the frame may be adjustably connect- 65 ed by bearings 4 having superposed openings 5. The wheel 3 is located close to one side of the frame 1 while the wheel 2 is located within the frame and inwardly from the other side thereof, thereby providing a space 70 on the frame between said wheel 2 and the side of the frame, for an engine 6. A supplemental frame 7 is pivotally connected to the frame 1 at the front of the engine side thereof and the rear portion of this frame 75 is adjustably connected to hangers 8 while the front portion is supported by casters 9. A draft tongue 10 may be attached to this supplemental frame and is adapted to be hitched to a team or to a tractor. With the 80 adjustable connections between the wheels 2 and 3 and their bearings and the adjustable connection between frame 7 and the hangers 8 the machine can be raised and lowered and tilted, as desired. 85

Arranged longitudinally of the machine close to the wheel 2 is a trough 11 which extends from the front portion of the frame 1 and rearwardly close to superposed feed rolls 12 and 13 located directly in front of 90 the inlet opening 14 of the housing 15 of an ensilage cutter 16, the knives 17 on said cutter coöperating with a stationary knife 18 located in the opening 14 as shown in Fig. 4. The housing 15 has a movable cover 95 19 whereby access can be had readily to the cutters and a discharge spout 20 extends downwardly from the housing.

The shaft 21 of the cutter 16 extends transversely of the machine and is provided 100 at one end with a fly wheel 22 while connected to its other end is a pulley 23 receiving motion through a belt 24 or the like from the wheel 25 on the engine shaft 26. A gear 27 is secured to the shaft 21 at one 105 side of the housing 15 and meshes with a gear 28 secured to one end of the shaft 29 of the lower feed roll 12. The shaft 30 of the upper feed roll 13 is journaled in the upper ends of standards 31 having springs 110 32 for thrusting them downwardly, thereby to press the roll 13 yieldingly against the

roll 12. Another gear 33 is secured to the shaft 29 at the other side of the housing 15 and constantly meshes with a gear 34 the shaft 35 of which is provided with a sprocket 36. A link 37 is mounted to swing on shaft 35 and has a stud 38 on which a gear 39 is journaled, this gear meshing with the gear 34. Another link 40 is pivotally mounted on the stud 38 and is engaged by the shaft 30, there being a gear 41 on said shaft meshing with the gear 39. See Figs. 6 and 7. Thus it will be seen that motion can be transmitted positively to both feed rolls 12 and 13 and, at the same time the roll 12 is free to move toward and from the roll 13.

Secured to the shaft 29 close to the gear 28 is a sprocket 42 adapted to transmit motion through a chain 43 to a sprocket 44 secured to a shaft 45. This shaft preferably alines with but is separate from the shaft 35. It extends transversely below the rear portion of the trough 11 (see Fig. 4) and carries sprockets 46 or the like on which is mounted an endless conveyer 47 the upper portion of which travels on the bottom of the trough. The front portion of the conveyer is supported by a shaft 48 close to the front of the frame 1. As shown, the conveyer is preferably formed of parallel chains connected by cleats 49. It will be obvious that, during the actuation of the ensilage cutter and the feed rolls, the conveyer will be operated to convey stalks, end first, from the front end of the machine rearwardly between the rolls 12 and 13 and to the cutter.

Suitably supported above the rear portion of the conveyer 47 and inclined downwardly and rearwardly toward the upper feed roll 13, is a frame 50 having shafts 51 and 52 journaled in the upper and lower portions thereof. These shafts carry rolls 53 on which is mounted an endless belt 54 having cross cleats 55. A sprocket 56 is secured to one end of the shaft 51 and receives motion through a chain 57 from the sprocket 36. The belt 54 serves to engage the ends of the stalks when fed toward the rolls 12 and 13 and direct them positively to the pass between the rolls.

Located at one side of the trough 11 and extending toward the wheel 3 is a table 58 above the side edge portions of which are journaled longitudinal shafts 59 and 60 carrying rollers 61 or the like on which is mounted a transverse conveying apron 62. This apron is of a width approximately equal to the length of the cut stalks and it is operated through gears 63 and 64 from a transverse shaft 65 extending along the front portion of the frame 1. Gear 63 is secured to shaft 60 while gear 64 is secured to the shaft 65. Another gear 66 is secured to shaft 65 and receives motion through a

gear 67 from a longitudinal shaft 68. A gear 69 is secured to the rear end of the shaft 68 and receives motion through a gear 70 secured to the shaft 21. Thus it will be seen that while the longitudinal conveyer 47 is being operated in the manner herein before described for directing stalks end first to the cutting mechanism in the housing 15, the apron 62 is also operated to convey transversely to the conveyer 47 all stalks deposited on said apron. This transverse movement of the stalks by the apron can be facilitated by securing sprockets 71 on the shafts 59 and 60 and mounting an endless chain 72 thereon, said chain having fingers 73 for engaging and dragging the heads of the stalks. A hood 74 is preferably arranged over the chain 72 and the rear end of the conveyer apron 62 for guiding the heads of the stalks positively to 85 position under the belt 54.

Secured on the front end of the frame 1 directly in front of the conveyer 47 is a tripping pan 75 open at the front end and having forwardly diverging side wings 76 extending therefrom. A stationary knife 77 is extended forwardly from the frame 1 between the wings 76. Another tripping pan 78 is mounted on the front of the frame 1 and in front of the apron 62 and is spaced 90 from the pan 75 a distance equal to the distance between two rows of standing stalks. The pan 78 is of the same construction as pan 75 with the exception that the rear portion of that side thereof nearest the conveyer 100 trough 11 is cut away, as at 79 thus to leave nothing for the stalks to hang onto and permit the butt ends of stalks to pass freely out of the pan when moved laterally by the apron 62. A stationary knife 80 extends forwardly from the frame 1 and between the wings of the pan 78. It is to be understood, of course, that if the machine is of sufficient width, several of the pans 78 may be used, one for a row, and the apron can convey cut 110 stalks from all of said rows to the trough 11. In the present instance only a two row machine has been shown, but by increasing the width three or more rows can be harvested simultaneously.

Mounted for reciprocation upon the front portion of the frame 1 is a bar 81 having cutting teeth 82 arranged in groups, one group cooperating with each knife 77 or 80. A pitman 83 connects one end of the bar to 120 a disk or crank 84 on the shaft 68. It will thus be seen that during the actuation of the conveyers 47 and 62 the teeth 82 will be reciprocated rapidly and the stalks standing in the paths thereof will be severed. As the 125 machine is advancing during this operation the butt ends of the severed stalks will move onto the pans 75 and 78 until they come against the back walls of the pans whereupon they will be tripped and fall rear. 130

wardly onto the conveyers 47 and 62 respectively.

Journalized on the front portion of the frame 1 are vertical shafts 85 receiving motion through gears 86 from the shaft 65. These shafts 85 are arranged in pairs, one of the tripping pans being extended between the shafts of each pair. The upper ends of the shafts are journalized in downwardly and 10 rearwardly inclined frames supported above the conveyers 47 and 62 and arranged in pairs, these frames being indicated at 87. The frames of each pair are spaced apart and each frame is formed of an upper and a 15 lower wall between which is arranged an endless chain 88. The chains have laterally extending fingers 89 adapted to project into the space between the frames, thus to engage stalks located between said frames. One of 20 the sprockets 90 on which each chain is mounted, is secured to a shaft section 91 connected by a universal coupling to the upper end of the adjacent shaft 85.

Upper and lower gathering frames 92 are 25 extended forwardly from the shafts 85 the corresponding frames on the shafts 85 of each pair coöperating to form stalk receiving spaces therebetween. Each frame is made up of upper and lower walls 93 suitably connected to each other and between the two walls are sprockets 94 and 95, the 30 sprockets 94 being secured to the shafts 85. Endless chains 96 are mounted on the sprockets and between the walls of the frames and 35 have laterally extending fingers 97 adapted to project into the spaces between the gathering frames. The stalk engaging portions of the chains may be provided with backings 98 formed of spring strips secured within 40 the frames, as shown in Figs. 11 and 12. The frames 92 of each pair are preferably fastened to each other by crossed braces 99 as shown. By providing the arrangement of gathering devices described and shown it 45 will be apparent that, as the machine is operated, the chains 96 will hold the stalks upright while being cut and, when the stalks pass onto the pans 75 and 78 they will be pulled thereover and be engaged by the fingers on the chains 88 which will, in turn, 50 draw the stalks downwardly and rearwardly so as to deposit them properly on the respective conveyers.

For the purpose of delivering the 55 comminuted ensilage from the machine, an inclined conveyer 100 is arranged to receive the material from the spout 20, this conveyer being operated by a chain 101 engaging sprockets 102 and 103 connected respectively 60 to the shaft 59 and the lower shaft 104 of the elevator.

What is claimed is:—

1. A machine for harvesting ensilage including a longitudinal conveyer, a tripping pan open at the front end and overhanging the front portion of the conveyer, stalk cutting mechanism in front of the pan, means for engaging the cut stalks and dragging them over the pan, means for directing the head ends of the stalks downwardly and rearwardly onto the conveyer. 65

2. A machine for harvesting ensilage including a longitudinal conveyer, a tripping pan at the front thereof and open at the front, gathering wings at the sides of the 75 pan, stalk severing means in front of the pan, spaced stalk gathering means, above and in front of the pan, for dragging severed stalks in upstanding positions over the pan thereby to trip the stalks, means for 80 directing the head ends of the tripped stalks downwardly and rearwardly onto the conveyer.

3. A machine for harvesting ensilage including a longitudinal conveyer, a transverse conveyer for directing material thereonto, a tripping pan adjacent the front portion of each conveyer, stalk severing means in front of each pan, means above each pan for gathering stalks and dragging them, 85 when severed, over the pan and in upstanding positions, until tripped by the pan, means for engaging the tripped stalks and lowering them rearwardly onto the respective conveyers to lie longitudinally of the 90 machine, stalk compressing means at the rear end of the longitudinal conveyer, and means for guiding the tops of the stalks on the transverse conveyer into position under 95 said compressing means. 100

4. A machine for harvesting ensilage including a longitudinal conveyer, an ensilage cutter at rear end thereof, delivering mechanism extending from the cutter, stalk compressing mechanism for directing stalks 105 from the conveyer to the cutter, a stalk cutter at the front end of the conveyer, a transverse conveyer for delivering stalks onto the longitudinal conveyer, and a stalk in front thereof, and means interposed between the 110 respective stalk cutters and the conveyers, for tripping the stalks, when cut and depositing them on the conveyers and longitudinally of the machine.

In testimony that I claim the foregoing 115 as my own, I have hereto affixed my signature in the presence of two witnesses.

LARK ATHEN SPROUL.
